UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 14, 1926. Serial No. 135,405.

My invention relates to railway traffic controlling apparatus, and particularly to apparatus of the type wherein train-carried governing mechanism is controlled by energy received from the trackway. More particularly my present invention relates to the trackway portion of such apparatus.

I will describe three forms of apparatus embodying my invention, and will then point out the novel features thereof in claims.

In the accompanying drawings, Fig. 1 is a diagrammatic view showing one form of apparatus embodying my invention. Figs. 2 and 3 are views showing modifications of the apparatus shown in Fig. 1 and also embodying my invention.

Similar reference characters refer to similar parts in each of the several views.

Referring first to Fig. 1, the reference characters 1 and 1^a designate the track rails of a railway along which traffic normally moves in the direction indicated by the arrow. These rails are divided by insulated joints 2 into a plurality of track sections, of which only one section A—B is shown in the drawing.

Located adjacent the exit end of the section A—B are two sources of current differing in frequency. As here shown, these sources are a transformer C⁶⁰ and a transformer C¹⁰⁰, the primaries of which are connected with alternating current generators which are not shown in the drawing. The frequencies of the currents delivered by these transformers may, for example, be 60 cycles per second and 100 cycles per second, although I do not wish to limit myself to these particular frequencies.

The section A—B is provided with a track circuit which is normally supplied with 60 cycle current from the transformer C⁶⁰, the secondary circuit for this transformer including the primary 19 of a track transformer T and the back contact 11—11^b of a coding device D hereinafter explained. The secondary 20 of transformer T is constantly connected across the rails of section A—B through a limiting impedance 21. Located at the entrance end A of the section A—B is track relay R^A having two windings 3 and 4, winding 3 being constantly connected with the track rails 1 and 1^a of section A—B. This relay is of a type requiring alternating currents of the same

frequency in its two windings 3 and 4 to effectively energize the relay, and as here shown, the relay is of the centrifugal type comprising a rotor 5 operated by the windings 3 and 4 and a back contact 10 which is open only when the centrifugal device 6 is rotating at or above a predetermined speed. Winding 4 is energized from the secondary of a transformer F⁶⁰, the primary of which is supplied with 60 cycle current from a suitable source, a resistance 34 being interposed between the secondary of F⁶⁰ and relay winding 4. It will be seen, therefore, that under normal conditions, that is, when the track section A—B is unoccupied, 60 cycle current is supplied to both windings 3 and 4 of relay R and so this relay is effectively energized to hold its back contact 10 open.

The coding device D comprises a winding 22 provided with a circuit which passes from terminal X of a suitable source of current, through back contact 10 of relay R^A, then through winding 22 and a back contact 13 of device D to terminal O of the same source of current. It follows that when back contact 10 is closed, the device D will be alternately energized and de-energized due to the fact that its own back contact 13 is included in the circuit of the operating winding 22, and so the contact 11 of this device will alternately engage contact points 11^a and 11^b. When contact 11—11^b of the coding device D is closed, the supply of 60 cycle current from the transformer C⁶⁰ to the track rails is discontinued, and 100 cycle current from the transformer C¹⁰⁰ is then supplied to the rails, the secondary circuit for transformer C¹⁰⁰ including contact 11—11^a and the primary 19 of the track transformer T. It follows that when a train occupies section A—B, so that the back contact 10 of track relay R is closed, the rails of this section are alternately supplied with 60 cycle current and with 100 cycle current.

The apparatus is intended for co-operation with train carried governing mechanism which responds to the intermittent supply of 100 cycle current but not to the continuous supply of such current or to 60 cycle current.

I have found that the centrifugal relay R^A may not become effectively energized to open its back contacts and close its front

contacts when winding 4 is constantly supplied with 60 cycle current and winding 3 is alternately supplied with 60 cycle and 100 cycle current, and so with the apparatus 5 thus far described this relay might not become effectively energized when a train passes out of section A—B. I have also found, however, that relay R^A will become effectively energized when 60 cycle current 10 and 100 cycle current are alternately supplied to winding 3 if the supply of 60 cycle current to winding 4 is discontinued during the intervals in which 100 cycle current is being supplied to winding 3, and I have accordingly provided means for accomplishing this result. Located adjacent the point 15 A is a "distant" relay H, which, together with track relay R^A , controls a wayside signal S^A through the medium of circuits which are well understood and which are, therefore, not shown in the present disclosure. Relay H is controlled jointly by relay R^A for track section A—B and by a similar track relay R^B for the section to the right of point 20 B, the circuit for relay H being from the secondary of a transformer E^{60} , through a resistance 35, front contact 7 of relay R^B , wires 14 and 14^a, winding of relay H, front contact 9—9^a of relay R^A , wire 15, and front 25 contact 8 of relay R^B to the secondary of transformer E^{60} . The primary of transformer E^{60} is supplied with current from a source not shown in the drawing. Connected across the terminals of winding 4 of relay R^A is the primary 23 of a transformer 30 G, and one terminal of the secondary 24 of this transformer is connected through wire 16 with wire 14 which is included in the circuit for distant relay H. When relay R^A is open, the other terminal of the secondary 35 24 of transformer G is connected through back contact 9—9^b with the wire 15, which is also included in the circuit for distant relay H. It follows that when relay R^A 40 is closed, the secondary 24 of transformer G is on open circuit, but that when relay R^A is open, the secondary 24 of transformer G is connected across wires 14 and 15. When the coding device D is energized, 45 wires 14 and 15 are connected by a low resistance path which includes wires 17 and 18 and front contact 12 of device D, so that if relay R^A is then open the secondary 24 of transformer G is placed on short circuit and so the supply of 60 cycle current from 50 transformer F^{60} is shunted away from winding 4 of relay R^A . The resistances 34 and 35 prevent the secondaries of transformers F^{60} and E^{60} from being placed on short circuit when wires 14 and 15 are connected by 55 contact 12.

The operation of the apparatus shown in Fig. 1 is as follows: Normally the coding device D is de-energized, so that 60 cycle current is supplied to track transformer T, and

the secondary 24 of transformer G is on open circuit, with the result that 60 cycle current is being supplied to both windings 3 and 4 of relay R^A . This relay is therefore effectively energized to open its back contact 10 70 and to close its front contact 9—9^a. When a train enters section A—B, it discontinues the supply of current to track winding 3 of relay R^A , so that this relay opens and thereby sets the coding device D into operation, 75 whereupon the rails of section A—B are alternately supplied with 60 cycle current and 100 cycle current. When the train passes out of section A—B, these two currents are alternately supplied to the track 80 winding 3 of relay R^A , and during the intervals in which 100 cycle current is being supplied to this winding, the 60 cycle current in winding 4 is discontinued because of the shunting effect of contact 12 of the 85 coding device D. The resulting intermittent supply of 60 cycle current to the windings 3 and 4 of relay R^A continues until the centrifugal device 6 is brought up to a speed high enough to open back contact 10, whereupon the coding device D stops operating and the continuous supply of 60 cycle current to both of the windings of relay R^A is resumed. Ordinarily the coding device D 90 will be controlled in part by traffic conditions in advance of section A—B, as well as by back contact 10 of relay R^A , but since this further control forms no part of my invention I have omitted it from the drawing in order to simplify the disclosure. 95

Referring now to Fig. 2, the apparatus here shown is the same as that shown in Fig. 1 except for the control of the coding device D and except for the fact that means are provided for preventing the intermittent supply of 60 cycle current while the coding device D is in operation if the intermittent supply of 100 cycle current fails. In Fig. 2 the circuit for the distant relay H is from the secondary of transformer E^{60} through contact 7 of relay R^B , wire 14, winding of relay H, front contact 9 of relay R^A , wires 15 and 15^a and contact 8 of relay R^B to the secondary of transformer E^{60} . The coding device D is controlled by a front contact 105 27 of a slow-releasing relay J, the circuit being from terminal X of a suitable source of current, through contact 27 of relay J, winding 22 of coding device D and back contact 13 of this coding device to terminal O of the same source of current. Relay J is connected with the output terminals of a full-wave rectifier K, which rectifier is normally de-energized. When track relay R^A is open, 110 however, the rectifier K becomes energized from transformer G, the circuit being from the secondary of transformer G, through wire 16, rectifier K, wire 23, back contact 12—12^b of coding device D, wires 18 and 15, 115 and the back point of contact 9 of relay R^A 120 125 130

to the secondary of transformer G. The primary of transformer G is, of course, energized from the secondary of transformer F⁶⁰. Each time that the front contacts of the coding device D become closed, wires 16 and 15 are connected together through wire 16^a, front contact 12—12^a and wire 18, so that the secondary of transformer G is then placed on short circuit; during these intervals of short circuit, the rectifier K and relay J are, of course, de-energized, but relay J is sufficiently slow-releasing to keep its front contact 27 closed during each of these intervals, so that the operation of the coding device D is not interfered with.

Under normal conditions, that is, when section A—B is unoccupied, the primary 19 of track transformer T is continuously supplied with 60 cycle current, the circuit being from the lower terminal of the secondary of transformer C⁶⁰ through wire 28, back contact 26 of relay J, wire 29, back contact 11—11^b of the coding device D, and the primary 19 of transformer T to the upper terminal of the secondary of transformer C⁶⁰. When relay J becomes energized due to a train entering section A—B, this circuit is opened, but the closing of front contact 11—11^a of the coding device D causes 100 cycle current to be supplied to transformer T through this front contact and through a reactance 24. Connected across the reactance 24 is a full-wave rectifier M, which supplies uni-directional current to a slow-releasing relay L. Relay L, therefore, becomes energized the first time that the front contacts of the coding device D close, and it thereafter keeps its front contact 25 closed as long as 100 cycle current is intermittently supplied to the track transformer, because of the slow-releasing characteristic of this relay. With front contact 25 of relay L closed, 60 cycle current is supplied to the primary of track transformer T each time that the back contacts of the coding device D become closed, the circuit being from the lower terminal of the secondary of transformer C⁶⁰, through contact 25 of relay L, back contact 11—11^b of coding device D, and the primary 19 of track transformer T to the upper terminal of the secondary of transformer C⁶⁰.

The operation of the apparatus shown in Fig. 2 will be apparent from the foregoing description and from the explanation given hereinbefore of the operation of the apparatus shown in Fig. 1. The reason for preventing intermittent supply of 60 cycle current if the 100 cycle current impulses are not also being supplied, is that 60 cycle impulses of high magnitude in the track rails may cause improper operation of the engine equipment if the alternate impulses of 100 cycle current are absent. In the event that the supply of 100 cycle current fails, it will

be obvious that relay L will remain de-energized, and since relay J is continuously closed while a train is in the section, there will be no 60 cycle current supplied to the track transformer T when the back contact 11—11^b of the coding device D is closed. In the event that this check on the supply of 100 cycle current is not required, the reactance 24, rectifier M, relay L, and back contact 26, may be omitted, the lower terminal of the secondary of transformer C⁶⁰ then being connected directly to contact 11^b of the coding device C.

Referring now to Fig. 3, the apparatus in the form here shown involves a modification of the means for controlling the operation of the coding device D and also a modification of the means for picking up the track relay R^A when a train passes out of the section A—B.

The circuit for the distant relay H is substantially the same as in Fig. 1, and will be understood without tracing in detail. The coding device D is controlled by a relay J^a in such manner that the device operates when the relay J^a is energized, the circuit for the operation of the coding device being the same as in Fig. 2. Relay J^a is connected across wires 14^a and 15, but this relay is designed to operate on direct current and not on alternating current, so that relay J^a is not effectively energized by current from transformer E⁶⁰ through contacts 7 and 8 of track relay R^B. When track relay R^A is de-energized, however, relay J^a is energized from a transformer N, through a full-wave rectifier P, the output circuit for the rectifier being from the upper terminal of the rectifier through back contact 9^b—9 of relay R^A, wire 15, winding of relay J^a and wires 14^a and 30 to the lower terminal of the rectifier.

When the back contacts of the coding device D are closed, 60 cycle current is supplied from transformer C⁶⁰ to the primary 19 of track transformer T and also to the primary 31 of a transformer Q. When the front contacts of the coding device D are closed, 10 cycle current is supplied from transformer C¹⁰⁰ to the primary 19 of track transformer T and also to the primary 31 of transformer Q. The secondary 32 of transformer Q is connected with winding 4 of track relay R^A through wires 33 and 15, so that this winding 4 is always supplied with current of the same frequency as that which is being supplied to the track rails through transformer T. It follows that when a train passes out of section A—B, track relay R^A will become effectively energized due to the alternate supply of 60 cycle current and 100 cycle current to its two windings 3 and 4. As soon as the back contact 9—9^b of relay R^A opens, the supply of uni-directional current from rectifier P to relay J^a will be discontinued, so that the operation of the cod-

ing device D will cease, whereupon 60 cycle current will be continuously supplied to the track rails and also to winding 4 of relay R^A.

The apparatus shown in Fig. 3 is an improvement on that shown in the application for Letters Patent of the United States, filed by Charles R. Beall, on or about the 4th day of August, 1926, Serial No. 126,970; by controlling the coding device D over the line 10 wires 14^a and 15 I am enabled to accomplish the same result with one less line wire than is required in the apparatus shown in the aforesaid application by Charles R. Beall.

Although I have herein shown and described only three forms of apparatus embodying my invention, it is understood that various changes and modifications may be made therein within the scope of the appended claims without departing from the spirit 20 and scope of my invention.

Having thus described my invention, what I claim is:

1. In combination, a section of railway track, a track relay having two windings one 25 of which is energized from the track rails of the section, two sources of alternating current differing in frequency, means for constantly supplying current to the rails of said section from the first of said sources when 30 said relay is closed and for supplying current alternately from the first and second sources to the rails when the relay is open, means for normally supplying the second winding of said relay with current of the 35 frequency of said first source, and means for discontinuing the supply of current to said second winding when current is being supplied to the rails from said second source.

2. In combination, a section of railway 40 track, a track relay having two windings one of which is energized from the track rails of the section, two sources of alternating current differing in frequency, means for constantly supplying current to the rails of said section from the first of said sources when 45 said relay is closed and for supplying current alternately from the first and second sources to the rails when the relay is open, means for normally supplying the second winding of said relay with current of the frequency of said first source, 50 and means for shunting current away from said second winding while current is being supplied to the rails from said second source.

3. In combination, a section of railway 55 track, a track relay having two windings one of which is energized from the track rails of the section, two sources of alternating current differing in frequency, a coding device controlled by said relay in such 60 manner that the device is at rest when the relay is closed and in operation when the relay is open, means controlled by said coding device when at rest for constantly supplying 65 current from said first source to the track

rails and when in operation for supplying current alternately from the first and second sources to the rails, means for normally supplying the second winding of said relay with current of the frequency of said first source, 70 and means controlled by said coding device for shunting current away from said second winding while current from said second source is being supplied to the rails.

4. In combination, a section of railway 75 track, a track relay having two windings one of which is energized from the track rails of said section said relay also comprising a centrifugal device actuated by currents in said windings, two sources of alternating 80 current differing in frequency, means for constantly supplying current to the rails of said section from the first of said sources when said relay is closed and for supplying current alternately from the first and second 85 sources to the rails when the relay is open, means for normally supplying the second winding of said relay with current of the frequency of said first source, and means for discontinuing the supply of current to said second winding when current is being supplied to the rails from said second source.

5. In combination, a section of railway 90 track, a track relay having two windings one of which is energized from the track 95 rails of said section said relay also comprising a centrifugal device actuated by currents in said windings, two sources of alternating current differing in frequency, a coding device controlled by said relay in such manner 100 that the device is at rest when the relay is closed and in operation when the relay is open, means controlled by said coding device when at rest for constantly supplying current from said first source to the track 105 rails and when in operation for supplying current alternately from the first and second sources to the rails, means for normally supplying the second winding of said relay with current of the frequency of said first source, 110 and means controlled by said coding device for shunting current away from said second winding while current from said second source is being supplied to the rails.

6. In combination, a section of railway 115 track, a track relay having two windings one of which is energized from the track rails of the section, two sources of alternating current differing in frequency, a coding device controlled by said relay in such 120 manner that the device is at rest when the relay is closed and in operation when the relay is open, means controlled by said coding device when at rest for constantly supplying current from said first source to the 125 track rails and when in operation for supplying current alternately from the first and second sources to the rails, means for normally supplying the second winding of said relay with current of the frequency of said 130

- first source, a distant relay for said section having a circuit controlled by traffic conditions in advance of the section, means operating when said track relay is open to connect said second winding with the circuit for said distant relay, and means controlled by said coding device for closing a low resistance shunt across said distant relay circuit while current from said second source 10 is being supplied to the rails of said section.
7. In combination, a section of railway track, a track relay having two windings the first of which is energized from the track rails of said section, a normally de-energized 15 slow-releasing relay, a transformer having its primary connected with a source of current of one frequency and its secondary connected with the second winding of said track relay, a second transformer having its primary connected with the secondary of said first transformer, means operating when said track relay is de-energized to supply said slow-releasing relay with current from the secondary of said second transformer, a coding device periodically energized while said slow-releasing relay is closed, means for placing the secondary of said second transformer on short circuit each time said coding device becomes energized, and means acting 20 while said coding device is in operation to alternately supply current of said one frequency and current of a different frequency to the rails of said section.
8. In combination, a section of railway 25
- track, means for alternately supplying currents of two different frequencies to the rails of said section, and means for preventing the supply of current of one said frequency to the rails of said section if the supply of current of the other frequency to the rails 30 of said section fails.
9. In combination, a section of railway track, a track relay having two windings the first of which is energized from the track rails of said section, a coding device arranged when in operation to alternately supply currents of two different frequencies to the rails of said section and to the second winding of said track relay, a distant relay 35 for said section, a line circuit for said distant relay extending through said section, and means including a portion of said line circuit for controlling said coding device by said track relay.
10. In combination, a section of railway 40 track, a track relay having a winding receiving energy from the rails of said section, a coding device arranged when in operation to alternately supply currents of two different frequencies to the rails of said section, a distant relay for said section, a line circuit for said distant relay extending through said section, and means including a portion of said line circuit for controlling said coding 45 device by said track relay.

In testimony whereof I affix my signature.

ROBERT M. GILSON.
